**COMBINED BLINKING DANGER SIGNAL AND
BARRICADE**

Seymour Sohn, Los Angeles, Calif.

Application September 11, 1956, Serial No. 42,899

Term of patent 14 years

(Cl. D72—1)

Fig. 1**Fig. 2****Fig. 3**

Figure 1 is a front elevational view of a combined blinking danger signal and barricade, showing my new design;

Figure 2 is a side elevational view thereof; and,

Figure 3 is a plan view thereof.

I claim:

The ornamental design for a combined blinking danger signal and barricade, substantially as shown.
